DES. 2206

Grace Newton Peirce, of Philadelphia, Penna.
Letters Patent No. 2206. Dated Octo. 17-1865,
Design for a Glass Bottle.

The schedule referred to in these Letters Patent and making part of the

To all whom it may concern:

Be it known that Grace Newton Peirce, of Philadelphia, in the County of Philadelphia, and State of Pennsylvania, have invented a new and unique form of Glass Bottle, and I do hereby declare the following to be a full and exact description thereof.

The nature of my invention is to have the Glass Bottle resemble a barrel on its side with the bung-hole raised and shaped in the form of the neck of an ordinary bottle, with one or more projections, blown in the bottle or barrel, on the opposite side from the neck or bung hole, designed and intended for the glass barrel stent or stand upon, thus avoiding the danger of turning or rolling over, when placed upon a flat surface. These glass bottles or barrels, to be of any requisite size to hold any desirable quantity.

What I claim as my invention and desire to secure by Letters Patent is The design for a bottle as shown and described.
